UNITED STATES PATENT OFFICE.

WILLIS H. BELKNAP, OF NEW YORK, N. Y.

RETENTION-SPRING FOR UMBRELLAS.

SPECIFICATION forming part of Letters Patent No. 252,990, dated January 31, 1882.

Application filed October 7, 1881. (No model.)

To all whom it may concern:

Be it known that I, WILLIS H. BELKNAP, of the city of New York, county of New York, State of New York, have invented certain new and useful Improvements in Retention-Springs for Umbrellas, of which the following is a specification.

This invention relates to the springs of umbrellas and parasols secured in the sticks and adapted to retain the runner in position when the umbrella or parasol is open or closed.

It consists in inclosing the springs or a spring-acting catch within a light metal case in such a manner that it is in condition to retain the runner as desired by merely fixing the case in a slot in the stick, the upper part of the case and the projecting catch being the only parts visible when so fixed in place, thus producing a better retention device and saving considerable time in securing them in the stick over the present method, which consists in securing a wire spring in an irregular-formed slot in the stick, requiring considerable adjustment and having an unsightly appearance when done.

Figure 1 of the accompanying drawings represents a side elevation of my improved retention device. Fig. 2 is a transverse section of the same, cut through the line *x x*. Fig. 3 is a side elevation with the side of the case removed. Fig. 4 is a plan view. Fig. 5 represents the form of the sheet metal for the case before it is bent into shape. Figs. 6, 7, 8, and 9 are modifications.

The whole of the case is of one piece of sheet metal cut out in the shape shown at Fig. 5, and then by suitable formers bent to form a narrow box, having the sides *a a'*, top *a²*, in which is a slot through which the catch *b* projects, and the flange *a³*, to form the bottom and ends, and the peak *a⁴*, which is bent over and into the side *a* to hold the parts together, as shown at Figs. 1 and 2. The retention-catch *b* is provided with a hole at its rear end and a lip, *b'*, at its front end, which limits the extension of it beyond the top *a²* by coming in contact with the under side of the top *a²* of the case. Between the under side of the catch *b* and the bottom of the case is placed the wire spring *c*. To form the pivot upon which the catch *b* turns, the sides *a a'* of the case are forced inwardly

into the hole at the rear end of the catch. The case may be first made complete, and the spring *c* and catch *b* passed through the slot in the top of it, and the sides then forced into the pivot-hole in the catch, or the case may be completed, with the exception of turning down the side *a*, the punctures being formed in the sides for the catch-pivot, the spring *c* and catch *b* then placed in position and the side *a* closed down and held in place, as before described.

d represents part of an umbrella-stick, in which a slot is cut of the shape and size of the case, and the side *a* may be provided with two or more pointed projections or spurs, *a⁵*, to be pressed into the bottom of the slot in the stick to assist in holding the retention device in place; but as an extra security I propose in most cases to pass rivet-pins through the stick and through the holes *a⁶* in the case.

Instead of pivoting the rear end of the catch *b* in the case it may be formed as shown at *b²*, Fig. 6, rounded, so as to turn against the end and top of the case when the front end of the catch is depressed.

In Figs. 1 and 2 my improved retention device is shown applied as a bottom or thumb spring to hold the runner *e* in position when the umbrella or parasol is closed, and it is equally well adapted as a top spring to hold the umbrella or parasol open.

In substitution for the catch *b* and spring *c*, the wire spring-catch *f* may be used, of the form and placed in the case as shown at Fig. 7.

Another modification is shown at Figs. 8 and 9, in which a spiral spring, *g*, is used in place of the spring *c*, the case having a cylindrical recess formed in it to hold the spiral spring, as clearly shown. Fig. 8 is a side elevation, and Fig. 9 a plan view.

I do not claim broadly a spring-acting catch, in combination with an inclosing case, as a spring-retainer for umbrellas.

Having now described my invention, what I claim, and desire to secure by Letters Patent, is—

1. In a retention device for umbrellas and parasols, in combination, a narrow case having a slotted top, a catch projecting through the slot and adapted to turn at its rear end in the case, and a spring located under the catch, sub-

stantially as and for the purpose hereinbefore set forth.

2. In combination with a spring-acting catch, *b*, an inclosing case *a a' a² a³ a⁴* therefor made of a single piece of sheet metal cut and formed into a narrow box and provided with holding-spurs *a⁵ a⁶*, substantially as hereinbefore set forth.

In witness whereof I have hereunto set my hand, at New York, county and State of New York, this 4th day of October, A. D. 1881.

WILLIS H. BELKNAP.

In presence of—

H. D. WILLIAMS,
E. G. BAKER.
